UNITED STATES PATENT OFFICE.

CORNELIA BITLER, OF FREDERICK, KANSAS.

HAT-BOX.

1,109,392.

Specification of Letters Patent.

Patented Sept. 1, 1914.

Application filed May 28, 1914. Serial No. 841,512.

To all whom it may concern:

Be it known that I, CORNELIA BITLER, a citizen of the United States, residing at Frederick, in the county of Rice and State of Kansas, have invented certain new and useful Improvements in Hat-Boxes, of which the following is a specification.

My invention relates to improvements in boxes to contain hats and has for its primary object to provide a box wherein one side thereof is removable thus enabling the contents of the box to be removed without necessitating removal of the lid at the top of the box.

15 Another object of importance is to provide a hat box of the character described that will open on the side thus enabling the storing of a large number of boxes one upon the other on shelves in stores or store rooms in such a manner that a person may readily remove the contents of any one of the boxes without having to lift the boxes off one another to remove the lid.

20 Another and more specific object is to provide a hat box that is formed of cardboard or the like and consists of a rectangular body having a flanged and removable lid or cover and a hinged side wall that is hinged to the box itself and is hinged intermediate its ends so as to be easily opened and moved into closed position.

25 My invention further aims to improve hat boxes so as to render them more practical, reliable and efficient, inexpensive to manufacture and more commercially desirable.

30 The above and additional objects are accomplished by such means as are illustrated in the accompanying drawings, described in the following specification and then more particularly pointed out as claimed.

35 With reference to the drawings, wherein I have illustrated the preferred embodiment of my invention as it is reduced to practice, and throughout the several views of which 40 similar reference numerals designate corresponding parts, Figure 1 is a side elevation of my improved hat box showing the hinged side in elevation, Fig. 2 is a vertical sectional view taken through my improved 45 box showing the hinged side in closed position, and Fig. 3 is a vertical sectional view showing the hinged side in open position.

50 Referring to the drawings by characters of reference, the numeral 1 designates as an 55 entirely a receptacle which consists of a

bottom wall 2 and side walls 3. The side walls 3 are secured to three of the edges of the bottom 2, said bottom being rectangular or square as desired, and to the other edge of the bottom 2 is secured a hinged wall 4. 60 A flanged lid 5 is arranged to be mounted upon the side walls 3 with its flanges 6 engaging the outer faces of the opposed side walls 3 adjacent the free vertical edges 65 thereof are vertical angle strips 7 that are approximately L-shaped in cross section and preferably formed of some relatively stiff cardboard. These strips 7 may be secured by fastening means, not shown, if desired, 70 but are preferably glued. Coöperating with the vertical strips 7 is a transverse strip 8 similar to the ones 7 and secured upon the upper face of the bottom wall 2. The strips 7 and 8 are arranged slightly spaced from 75 the free vertical edges of the side walls and the outer edge of the bottom wall respectively and act as a stop and brace for the hinged side 4 when said side is in closed position as shown in Fig. 2 in the drawings. 80 The hinged side 4 comprises a lower rectangular hinged section 9 that is hinged at its lower longitudinal edge to the bottom wall 2 by means of a flexible preferably fabric strip 10 that is glued or otherwise 85 suitably secured to the portion 9 and wall 2. Hinged to the upper longitudinal edge of the section 9 is an upper hinged section 11 that is of the same length as the section 9 and hinged by means of a fabric strip 12 90 similar to the one 10.

95 Secured upon the outer faces of the sections 9 and 11 and to the sections 9 and 11 are elastic strips 13 that serve to hold the upper section 11 in closed position and in engagement with the adjacent flange 6 of the lid 5 when in closed position. These strips 13 are secured at their ends to the sections 9 and 11 at the points where said sections are hingedly connected with each other. When the side 4 is in closed position as illustrated in Fig. 2 in the drawings, the inner faces of the sections 9 and 11 engage certain angular portions of the angular strips 7 and 8 and the outer face of the upper section 11 engages the inner face of the adjacent flange 6. It will thus be seen that the side is securely held in closed position.

100 Secured at one end as at 14 to the central 105

110

portion of the upper section 11 is a flexible element 15 that is extended inwardly and passed through the lower section 9 from the inside thereof and disposed at its free end exteriorly of the box. Reinforcing portions 16 are secured to the sections 9 and 11 at points where the flexible element 15 passes therethrough.

To open the hinged side 4 the operator 10 grasps the flexible element 15 and communicates a pull thereto causing the upper section 11 to move inwardly out of engagement with the flange 6 at which time the side is free to be opened outwardly. In this connection 15 it will be noted that the strips 7 on the sides of the walls 3 are spaced from the upper longitudinal edges of the side walls sufficiently to enable the inward drawing of the upper section 11 when a pull is communicated to the flexible element 15. To close 20 the box the operator grasps the string 15 and pulls the upper section 11 into position as shown in Fig. 3 in the drawings which is approximately at right angles to the lower 25 section 9. It will be clearly seen that when the side is in this position it may be readily forced into closed position as shown in Fig. 2 in the drawings. The upper longitudinal edge of the section 11 is preferably reinforced by means of a metallic strip 17 bent to engage opposite sides of the portion 11. 30 In practice, I have found that the form of my invention, illustrated in the drawings and referred to in the above description, as 35 the preferred embodiment, is the most efficient and practical; yet realizing that the conditions concurrent with the adoption of my device will necessarily vary, I desire to emphasize the fact that various minor 40 changes in details of construction, proportion and arrangement of parts may be resorted to, when required, without sacrificing

any of the advantages of my invention, as set forth.

What is claimed is:—

1. A hat box comprising a bottom wall, side walls secured to three of the edges of the bottom wall, a hinged side wall hingedly secured to the bottom wall on the free edge thereof, strips secured on the inner faces of the opposed side walls and on the bottom wall to engage the hinged side when said side is in closed position, a flanged cover for the box, the upper edge of the hinged side wall to engage the inner face of the adjacent flange on the cover, said side wall comprising two sections hingedly connected with each other and a flexible element secured to the upper section and extended through the lower section on the inside thereof. 41 50 55

2. A hat box consisting of a bottom wall, side walls secured to three of the edges of the bottom wall, and to each other, a flanged lid mounted upon the side wall and a hinged side wall hinged at its lower edge to the 60 bottom wall at the free edge thereof and arranged to engage the inner face of the adjacent flange on the lid when in closed position, said hinged side wall consisting of two sections being hinged to each other, 65 elastic strips secured at their ends to the sections and serving to hold the upper of the sections in engagement with the inner face of the adjacent flange on the cover and a flexible element secured to the upper section and extended from the inner face of the 70 lower section through to the outer face thereof. 75

In testimony whereof I affix my signature in presence of two witnesses.

Mrs. CORNELIA BITLER.
